UNITED STATES PATENT OFFICE

RICHARD W. BURNETT, OF CHICAGO, ILLINOIS

RAILWAY CAR HAND BRAKE

Application filed March 25, 1929. Serial No. 349,817.

This invention relates to manually operated brake mechanisms for railway cars.

One of the objects of the invention is to provide a railway car hand brake in the operation of which the slack in the brake rigging and brake setting apparatus is quickly taken up, the brake shoes brought into contacts with the car wheels, with the parts of the brake setting apparatus in positions to give substantially maximum leverage, for all normal amounts of slack (piston travel) while provision is made for setting the brakes, though less effectively, even where, as may happen in a few isolated cases, there is an excessive amount of slack up to, for example, the full piston travel of the air brake cylinder piston plus the slack in the brake setting apparatus itself.

Another object of the invention is to provide, in a hand operated brake apparatus in which the chain of the brake rigging extends around a sheave, novel means for providing connections between the brake rigging and the operating mechanism on the end wall, for example, of the car.

By "brake rigging" I mean the apparatus under the car body including brake shoes, beams, equalizing and pulling rods, etc., which apparatus is ordinarily operated by compressed air but under certain conditions may require to be operated manually. By "chain" I intend to include any flexible connecting element, and by the term "bellcrank" a pivoted or rocking element to which the brake rigging is attached and which is oscillated by the hand-brake apparatus to set or release the brakes.

The invention is illustrated in certain preferred embodiments in the accompanying drawings wherein:

Fig. 1 is a fragmentary side elevation of a railway box car showing the brake of my invention applied thereto.

Fig. 2 is a fragmentary front elevation of the manually operated brake setting and releasing mechanism, the scale being larger than that of Fig. 1.

Fig. 3 is a vertical sectional view on line 3—3 of Fig. 2.

Figs. 4, 5 and 6 are diagrams illustrating

the relative positions of the bellcrank and drum for different piston travels. Fig. 4 represents the parts in their initial position, Fig. 5 in their brake setting position, for cars having normal slack and Fig. 6 the positions assumed by the parts with the extreme piston travel.

Fig. 7 is a view similar to Fig. 1 showing a modified apparatus in which a sheave is substituted for a rocking member.

Fig. 8 is a sectional plan on line 8—8 of Fig. 7.

Referring first to Figs. 1, 2 and 3, 25 designates the body of a railway box car, 26 a chain which forms part of the brake rigging of the car, 27 a rocking member or bellcrank pivoted at 28 to the bottom of the car and provided, preferably with an arcuate winding surface 29 for the chain 26. 30 is a rod pivoted at 31 to bellcrank 27 and 32 a chain which is adapted to be wound upon a drum 33 for setting the brakes through rocking movement of bellcrank 27.

The drum 33 is fixed to a shaft 34 pivoted in the back wall 35 and front wall 36 of a housing 37 which is closed at the top and open at the bottom and secured to the end wall of the car. Drum 33 has an arm 38 to which the chain 32 is attached in any suitable manner, the drum being preferably formed with a groove 39 for the chain. Fixed to shaft 34 is a large gear 40 which meshes with a smaller gear 41 on a shaft 42 pivoted in the housing 37 and projecting through the front wall thereof. Secured to the forwardly projecting end of shaft 42 is a holding ratchet 43 and a hand wheel 44. A holding dog 45 is pivoted at 46 to an upstanding flange 47 on housing 37 and is formed with a tooth 48 to engage the teeth of the ratchet 43. The forward end of dog 45, designated 49, is engaged by a tripping member 50 pivoted to flange 47 at 51. The tripping member has a weighted end 52 for holding the dog in engagement with ratchet 43. The trip 50 is provided with a lug 53 adapted to bear on the under side of the projection 49 of arm 45 to disengage the dog from the ratchet. 54 is a stop pin on a bracket 54a, forming part of flange 47, against

which stop pin the weighted end 52 bears 100.

when the trip is turned to its tripping position.

For instantaneous release of the brakes a rod 55 is provided which is pivoted at 56 to the flange 47 of housing 37 and is formed with tripping lugs 57 adapted to bear against a tail-piece 58 on the dog.

No claim is made to the holding and releasing mechanism just described, or to the combination of the same with the vertical hand wheel, as these devices and combinations are claimed in my co-pending application filed October 31, 1927 as Serial No. 229,967 (patented as Patent No. 1,879,973, dated September 22, 1932) and in my co-pending application Serial No. 281,088 filed May 28, 1928. This application is a continuation in part of application Serial No. 10,248 filed February 19, 1925 and since abandoned.

It will be observed that the winding chain 32 is attached to the drum at its longest radius. The drum is formed with a section of minimum and equal radius, designated *b*, *a* designating the long radius portion of the drum to which the chain is attached. *c* designates a section of gradually increasing radius and *d*, a section of decreasing radius.

By reference to Figs. 4, 5 and 6, it will be seen that provision is made for quick take-up of the slack after which the parts of the brake setting mechanism are in such position as to give maximum leverage in setting the brakes, where the piston travel is not excessive, while with extreme piston travel the brakes can still be set but with less favorable leverage conditions.

In a very great proportion of railway cars the brake shoes will be brought into contact with the wheels at somewhere between four and eight inches of piston travel. The winding drum 33 is designed to give the highest efficiency under these conditions. That is with any usual amount of slack (piston travel) the chain 32 will come into contact with the drum somewhere along section *b* of the drum, as shown in Fig. 5, Fig. 4 representing the initial position of the parts. At this time the bellcrank 27 will be in position to give maximum leverage, so that considering both the position of the drum and the position of the bellcrank, the apparatus is in condition to give the maximum, or very nearly the maximum power in applying the brakes with comparatively little variation for all points of contact along section *b* of the drum.

However, there may occasionally be a car which through wear of the parts or maladjustment will have enough slack in the brake connections to allow piston travel in excess of eight inches. Under these conditions the brake must be capable of operation, and, as it is more essential that the brakes should be capable of being set even with sixteen inches of slack, for example, so as to take care of a few emergency cases than that the brake

should be so designed as to have maximum efficiency for the relatively few instances of piston travel over eight inches and less than sixteen inches, the sections *c* and *d* of the drum are given increasing and decreasing radii, to make the brake operative for the very extreme amount of slack at the expense of diminished efficiency in the cases of abnormal piston travel, which will be few. Fig. 6 shows the parts in the relative positions which they will assume where the slack is excessive.

A modification is shown in Figs. 7 and 8. The chain 61 of the brake rigging in this case extends around a sheave 62 pivoted in a guide housing 63 at the bottom of the car. In order to prevent the inconveniences of a long chain which is likely to get out of alignment with its sheave and to be knocked against the car wall with the stopping and starting movements of the car, a rod 64 is interposed between the end of chain 61 and the chain 65 which is wound on the winding drum in the manner described in connection with the form of the invention shown in Figs. 1, 2 and 3. Rod 64 extends through guides 66, 67 which are preferably slotted as indicated at 68, Fig. 8. The connecting device 69 between chain 65 and rod 64 provides a stop coating with the upper guide 66. In the arrangement shown in Fig. 3 stops 70, 71 are provided on gear 40 and the back plate of the housing respectively. Both limiting means need not be provided.

A winding drum formed with its winding surface of the contour herein shown and described, that is with the chain attached to the drum at the point of longest radius, and in contact with the drum at the minimum radius section for braking operation in cars of normal piston travel is particularly suitable in the case of a brake apparatus, such as shown in Figs. 7 and 8 employing a sheave in place of the rocking member or bellcrank. The attachment of the chain to the drum at a point of long radius, viz. at the end of arm 38, gives quick take-up, requiring little power, while for braking operations on all normal cars the power which can be developed due to the short radius of section *b* of the drum is considerable.

The principal use of hand brakes on railway freight cars is in switching the cars in railroad yards although hand brakes are also used for holding a train on a siding when detached from the locomotive. In switching freight cars in the making up of a train, for example, in a hump yard, the hand brake is used for controlling a car, or cut of cars, as it slides down the incline toward the standing car to which it is to be attached. In this operation it is of the utmost importance that the action of the brake be positive, that the slack in the brake rigging be capable of being taken up very quickly, to bring the brake

shoes against the wheels and that when the slack has been so taken up the brake shoes should be capable of being applied to the wheels with great force. Accidents to brakeman and damage to cars and their cargoes are very largely due to deficiencies in hand brakes in one or more of the respects noted. The standard type of freight car brake involving a brake-mast on which the chain of the brake rigging winds, provided with a horizontal hand wheel, has been the cause of many accidents due to the slipping of the chain on itself as it winds on the brake mast and also to the fact that the brake hand wheel being horizontally placed is limited in diameter by end clearance requirements necessitating the use of a club in order to get adequate leverage, both in the setting and release of the brakes. Also the take-up of the brake rigging chain is necessarily slow.

The present invention, in each embodiment obviates these difficulties and thereby provides a hand brake which reduces accidents to a minimum. The chain winds on a drum of sufficient circumference so that there is no overlapping of the chain on itself, the winding surface of the drum being in the same plane with the length of chain extending therefrom toward the bottom of the car; that is the center line of the winding surface is in a single plane parallel to the end of the car. This arrangement makes the apparatus positive in its operation and reduces friction. The hand wheel is arranged vertically, making it possible for the brakeman to operate the brakes from a platform on the end of the car, or by standing on the end ladder, that is in a position much more secure than the top of the car where a brakeman must stand in operating the old type of brake referred to. Moreover by having the wheel arranged vertically it may be made of any reasonable diameter necessary to give adequate leverage. The slack in the brake rigging is quickly taken up, due to the operation of the bell crank, in one type of the invention and to the configuration of the winding drum in the other. At the same time when the drum reaches the brake setting position (for average equipment) the power is multiplied so that with a fairly large hand wheel, possible because of the vertical position of the wheel, a brakeman can hold onto the car with one hand and easily set the brakes with his other hand to give a braking pressure in excess of that required by railroad regulations in air brake operation.

The arrangement and construction herein described whereby the brakeman may maintain secure footing on the car and operate the brake without the use of the weight of his body in the brake operation are important contributions not only in the efficiency of the brake operation but also in the provision of greater safety to the brakeman.

I claim:

1. In combination with the brake rigging of a railway car, manually operated mechanism for setting the brakes comprising a vertically arranged hand wheel on the car and power increasing and transmitting mechanism between the brake rigging and the hand wheel comprising a chain and a drum having an eccentric winding surface the center line of which is in a single plane, the drum being formed with a section of relatively long radius to which the chain is attached, a section of short, substantially uniform, radius on which the chain first winds in setting the brakes and a section of increasing radius, over which the chain next winds if excessive slack permits, and an anti-friction element for transmitting movement from the chain to the brake rigging.

2. In combination with the brake rigging of a railway car, manually operated mechanism for setting the brakes comprising a vertically arranged hand wheel and power increasing and transmitting means between the brake rigging and hand wheel comprising a chain and a drum having an eccentric winding surface the center line of which is in a single plane, the drum being formed with a section of relatively long radius to which the chain is attached, a section of short, substantially uniform, radius on which the chain first winds in setting the brakes and a section of increasing radius over which the chain next winds if excessive slack permits, a rod attached to said chain, a chain attached to the other end of the rod and a sheave around which said last named chain extends.

3. In combination with the brake rigging of a railway car, manually operated mechanism for setting the brakes comprising a vertically arranged hand wheel and power increasing and transmitting means between the brake rigging and hand wheel comprising a chain and a drum having an eccentric winding surface the center line of which is in a single plane, the drum being formed with a section of relatively long radius to which the chain is attached, a section of short, substantially uniform, radius on which the chain first winds in setting the brakes and a section of increasing radius over which the chain next winds if excessive slack permits, a rod attached to said chain, a chain attached to the other end of the rod, a sheave around which said last named chain extends, and means for guiding the chain in its path of movement around said anti-friction element.

4. In combination with the brake rigging of a railway car, a vertically arranged hand wheel on the car, a revoluble anti-friction member near the bottom of the car, and power increasing and transmitting mechanism between the hand wheel and brake rigging comprising an eccentric winding drum and a connecting element having a flexible portion

attached to the winding drum at a wide part thereof and a flexible portion extending around the anti-friction member, said eccentric drum having a circumferential winding surface with its center line in a plane and longer than the maximum take-up of the slack in the brake rigging.

5. In combination with the brake rigging of a railway car, a vertically arranged hand wheel on the car, a revoluble anti-friction member near the bottom of the car, and power increasing and transmitting mechanism between the hand wheel and brake rigging comprising an eccentric winding drum, 10 a connecting element having a flexible portion attached to the winding drum at a wide part thereof and a flexible portion extending around the anti-friction member, said drum having a circumferential winding surface 15 with its center line in a plane and longer than the maximum take-up of the slack in the brake rigging and being operatively connected with the hand wheel so as to rotate in both directions with said wheel.

20 25 6. In combination with the brake rigging of a railway car, a vertically arranged hand wheel on the car, a revoluble anti-friction member near the bottom of the car, and power transmitting mechanism between the hand wheel and brake rigging for effecting a quick take-up in slack and for increasing the power comprising an eccentric winding drum, a connecting element having a flexible portion attached to the winding drum at a wide part thereof and a flexible portion extending around the anti-friction member, 30 said drum having a circumferential winding surface with its center line in a plane and longer than the maximum take-up of the slack in the brake rigging and gearing for operatively connecting the drum with the hand wheel whereby the drum rotates in both directions with the hand wheel.

35 40 45 7. In combination with the brake rigging of a railway car, a vertically arranged hand wheel on the car, a revoluble anti-friction member near the bottom of the car, and power increasing and transmitting mechanism between the hand wheel and brake rigging comprising an eccentric winding drum and a connecting element having a flexible portion attached to the winding drum at a wide part thereof and a flexible portion extending around the anti-friction member, said drum 50 having a circumferential winding surface with its center line in a plane and longer than the maximum take-up of the slack in the brake rigging, a small gear rigidly connected with the hand wheel and a large gear meshed therewith and rigidly connected with the drum.

55 60 65 8. In combination with the brake rigging of a railway car, a vertically arranged hand wheel on the car, an anti-friction member near the bottom of the car, and power increas-

ing and transmitting mechanism between the hand wheel and brake rigging comprising an eccentric winding drum, a connecting element having a flexible portion attached to the winding drum at a wide part thereof and a flexible portion extending around the anti-friction member, said drum having a circumferential winding surface with its center line in a plane and longer than the maximum take-up of the slack in the brake rigging, said connection comprising a vertically arranged rod and two sections of chains.

70 75 9. In combination with the brake rigging of a railway car, a vertically arranged hand wheel on the car, a revoluble anti-friction member near the bottom of the car, and power increasing and transmitting mechanism between the hand wheel and brake rigging comprising an eccentric winding drum and a connecting element having a flexible portion attached to the winding drum at a wide part thereof and a flexible portion extending around the anti-friction member, said drum having a circumferential winding surface with its center line in a plane and longer than the maximum take-up of the slack in the brake rigging, said connection comprising a vertically arranged rod and two sections of chains, and guiding means on the car for the rod.

80 85 90 95 100 105 110 115 120 125 130 10. In combination with the brake rigging of a railway car, a vertically arranged hand wheel on the car and power transmitting mechanism between the hand wheel and brake rigging, the power ratio of which is increased as the hand wheel is rotated in the direction to set the brakes comprising a winding drum having a circumferential winding surface with its center line in a plane and longer than the maximum take-up of the slack in the brake rigging, a chain to wind on said drum and means for changing the vertical pull on said chain to a horizontal pull on the brake rigging.

110 115 120 125 130 11. In combination with the brake rigging of a railway car, a vertically arranged hand wheel on the car and power transmitting mechanism between the hand wheel and brake rigging, the power ratio of which is increased as the hand wheel is rotated in the direction to set the brakes comprising an eccentric winding drum having a circumferential winding surface with its center line in a plane and longer than the maximum take-up of the slack in the brake rigging, a chain to wind on said drum and means for changing the vertical pull on said chain to a horizontal pull on the brake rigging.

120 125 130 12. In combination with the brake rigging of a railway car, a vertically arranged hand wheel, and power transmitting mechanism between the hand wheel and the brake rigging, the power ratio of which increases as the hand wheel is rotated in the direction to set the brakes, comprising a chain, a verti-

- cially arranged winding drum for said chain, having a circumferential winding surface with its center line in a vertical plane, a gear wheel on the same axis and connected with 5 the winding drum, a shaft with which the hand wheel is connected, a gear on said shaft engaged with the other gear and means for converting the vertical pull on said chain to a horizontal pull on the brake rigging.
- 10 13. In combination with the brake rigging of a railway car, a vertically arranged hand wheel, and power transmitting mechanism between the hand wheel and the brake rigging, the power ratio of which increases as 15 the hand wheel is rotated in the direction to set the brakes, comprising a chain, an eccentric vertically arranged winding drum for said chain having a circumferential winding surface with its center line in a vertical plane 20 to which the chain is attached, a gear wheel on the same axis and connected with the winding drum, a shaft with which the hand wheel is connected, a gear on said shaft engaged with the other gear, and means for converting 25 the vertical pull on said chain to a horizontal pull on the brake rigging.
